UNITED STATES PATENT OFFICE.

JOHN WOOD, OF BROOKLYN, NEW YORK.

MACHINE FOR CUTTING AND FOLDING WADDING AND PAPER.

Specification of Letters Patent No. 23,802, dated April 26, 1859.

To all whom it may concern:

Be it known that I, JOHN WOOD, of Brooklyn, in the county of Kings and State of New York, have invented a new and Improved Machine for Cutting and Folding Wadding, Paper, &c.; and I do hereby declare that the following is a full, clear, and exact description of the same, reference being had to the annexed drawings, making a part of this specification, in which—

Figure 1, is a vertical section of my invention, taken in the line x, x , Fig. 3. Fig. 2, a vertical section of ditto, taken in the line y, y , Fig. 3. Fig. 3, a plan or top view of ditto. Fig. 4, a detached view of a portion of the device which actuates the fly boards of the receiving boxes. Fig. 5, a detached view of another portion of ditto.

Similar letters of reference indicate corresponding parts in the several figures.

This invention is designed for cutting and folding wadding, paper, or any textile or pliant substance which is manufactured in continuous sheets or rolls and which require to be cut into pieces and folded for after use.

To enable those skilled in the art to fully understand and construct my invention I will proceed to describe it.

A, represents a rectangular frame in the upper part of which endless aprons B, are placed, said aprons passing around the same rollers a, b , which are placed at the ends of the frame A. The aprons B, B, are placed side by side, as shown clearly in Figs. 2 and 3. At the front end of the frame A, there are two feed rollers C, C, which are placed one over the other in the same plane and have a transverse position with the aprons B, B. At the front end of the frame A, there is fitted in suitable guides c , a reciprocating gate or sash D, in the upper part of which an oblique knife E, is placed. The knife E, works up and down between the inner sides of the rollers C, C, and the aprons B, B, as shown clearly in Figs. 1 and 3.

F, is a shaft which is placed transversely in the frame A, and is the power or driving shaft. This shaft F, has a pinion d , at one end of it and also a pulley e . The pinion d , gears into a wheel G, which is placed on one end of a shaft H, in the frame A. The wheel G, has a cam f , attached to its inner side as shown clearly in Figs. 1, 2 and 3. On the same shaft H, and adjoining the wheel G, a wheel I, is attached, said wheel being toothed on part of its periphery,

and having a hook-shaped cam J, attached to its outer side. This hook is shown clearly in Fig. 3.

The toothed portion of the wheel I, gears intermittently into a wheel K, which is at one end of shaft L, of the apron roller a . The wheel K, gears into a pinion g , which gears into the pinion h , of the lower feed roller C, the two feed rollers being connected by gears h , as shown in Fig. 1.

On the upper part of the frame A, there are placed two longitudinal rollers M, M'. These rollers extend about half the length of the frame A, and one of them, the roller M', is covered by a cap N, said cap being a portion of a hollow cylinder, having one edge nearly in contact with roller M, and the other end projecting upward and over the top portion of roller M', see more particularly Fig. 2.

In the frame A, a lever O, is placed, i , being its fulcrum pin as shown clearly in Fig. 1. This lever has a sector rack j , at each end of it. The rack at one end gearing into a rack k , attached to the back side of the gate or sash D, and the rack at the opposite end gearing into a similar rack k , on a vertical bar l , to the upper end of which a horizontal plate P, is attached, said plate being in line with the "bite" of the rollers M, M'.

On the shaft H at about its center a wiper Q, is placed. This wiper actuates the lever O, and has two arms m, n , one of which m , depresses the lever at the end near the gate or sash D, the other arm n , elevating said end.

The wheel I, gears intermittently into a wheel R, which is placed on one end of a shaft S, said shaft being on the upper part of the frame A, and having two bevel pinions o, o , placed on it which pinions gear into corresponding pinions p, p , attached to the shafts of the rollers M, L', see Fig. 3.

T, is a fly which is constructed by attaching a series of rods q , to a shaft r , as shown clearly in Fig. 3, the shaft r , being allowed to turn freely in its bearings. On one end of shaft r , a pinion s , is placed, into which a rack t , on the upper end of a spring plate u , is placed, said plate having a friction roller v , attached to one side of it, the roller being within the plane of the movement of the cam f , of wheel G.

U, represents a series of endless tapes or carriers which pass around the roller

M' , and a series of pulleys u , on a shaft x , near and parallel with the shaft r , of the fly T .

V , is a receiving box which has two compartments formed by a central partition a' . These compartments have open sides and tops, and the box is allowed to turn freely on the upper end of an upright W . To the under side of the receiving box V , two tubes b' , b' , are attached, one underneath each compartment. To the lower ends of these tubes a toothed wheel or rim X , is attached. In each tube b' , a rack c' , is placed. The upper ends of these racks are attached to the under sides of plates or boards d' , d' , which are fitted in the compartments of the receiving box V , one in each, and allowed to move freely up and down therein. In each rack c' , a pinion e' , gears. These pinions are placed on shafts f' , underneath the box V , said shafts having each a spiral spring g' , placed on them and a ratchet h' , at their outer ends. One end of the springs g' , are attached to the shafts f' , and the other to the under side of the box V . In each ratchet h' , a holding pawl i' catches, and also an actuating pawl j' , the latter being attached to arms k' , the upper ends of which are provided with inclined planes l' , the use of which will be presently shown.

Around the pulley e , of the shaft F , a belt m' , passes. This belt also passes around a pulley n' , at the inner end of a shaft o' , the outer end of which has a pinion o'' , on it and its bearing in a vertical plate p' , which is attached to a yielding plate q' .

The operation is as follows:—Motion is given the shaft F , in any proper manner, and as said shaft rotates a reciprocating motion is given the knife gate D , and plate P , in consequence of the action of the wiper Q , on said lever. An intermittent movement is also given the endless aprons B , B , in consequence of the wheel I , being smooth on part of its periphery. For the same reason the rollers M , M' , have an intermittent motion. The material to be cut and folded passes between the rollers C , C , on the endless aprons B , B , and as the gate D , descends at regular intervals the knife E , cuts the material into pieces of equal lengths. The gate D , and aprons B , B , move alternately and therefore when the knife E , is raised and stationary the aprons B , move the piece cut off by the knife E , at its previous descent, underneath the rollers M , M' . The aprons B , B , then stop and the gate D , again descends and cuts off a succeeding piece and as the gate ascends, the rollers M , M' , rotate and draw between them in a folded state the piece underneath them, see a'' , the plate P , rising as the gate D , descends and presenting the center of the piece to the bite of the rollers M , M' . The piece

a'' , is carried up between the rollers and passes over the roller M' , on the tapes U the cap N , effecting such result, and when the piece a'' , is fully extended on the tape the fly T , is actuated by the cam f , spring plate u , and rack t , and the fly throws the piece a'' , on the board d' , in the compartment of the box V , that is opposite it. A each cut piece a'' , is thrown in the compartment by the fly T , the board d' , is depressed to a certain extent, a distance equal to the thickness of the stuff by means of the cam J , which actuates the arm k' , in consequence of its passing behind the inclined projection l' and the rack c' , that is attached to the board d' , is of course depressed or forced down in its tube b' , and retained as it is forced down by the pawl i' , which catches into the ratchet h' , the spring g' , is also wound up at the same time or at each downward movement of the rack c' , when the board d' , reaches the bottom of its compartment, the compartment of course will be filled and the rack c' will at such time depress the plate q' , and thereby throw the pinion o'' , in gear with the wheel X , and turn the box V , one half of a revolution so that the empty compartment will be opposite the fly T , the plate q' having a small projection o''' , on its upper surface which projection catches into the bottom of the tube b' , and retains the box V the pinion o'' , being out of gear from its wheel. The operator then removes the folded pieces from the filled compartment and throws up the retaining pawls i' , j' , which are connected with the ratchet h' , of said compartment and the spring g' , on the shaft f' connected with said compartment throws up the board d' , so that said compartment will be ready to be again filled in turn. It will be seen that by this arrangement the pieces are all counted as each box contains a certain number of pieces corresponding to the number of times its board d' , is depressed.

This invention it will be seen works automatically throughout. It requires no attention except the taking or removing of the folded or cut pieces from the filled compartments of the box V , and the material operated on may pass between the rollers C , C , direct from the machine where it is manufactured.

Having thus described my invention what I claim as new and desire to secure by Letters Patent, is—

1. The receiving box V , provided with two compartments and fly boards d' , connected with rack c' , and with ratchets h' , actuated by the arms k' , and cam J , in connection with the wheel X , and adjustable pinion o''' , substantially as and for the purpose set forth.

2. Operating the knife gate D , and plate P , by means of the lever O , provided with

sector racks *j*, which gear into the racks *k*, of the gate *D*, and bar *l*, so that the knife and plate will be actuated or made to perform their respective functions alternately as described.

3. The arrangement of gearing *G*, *I*, *K*, *R*, as shown and described, when used in

connection with the lever *O*, for the purpose of operating the several parts automatically as and for the purpose set forth.

JOHN WOOD.
